UNITED STATES PATENT OFFICE.

ORVILLE G. WALLACE, OF ROXBURY, OHIO.

CASTER.

1,127,125.

Specification of Letters Patent.

Patented Feb. 2, 1915.

Application filed April 1, 1914. Serial No. 828,854.

To all whom it may concern:

Be it known that I, ORVILLE G. WALLACE, a citizen of the United States, residing at Roxbury, in the county of Morgan and State of Ohio, have invented certain new and useful Improvements in Casters, of which the following is a specification, reference being had to the accompanying drawings.

This invention relates to certain improvements in casters and has relation more particularly to a device of this general character employing a large or main ball adapted to travel on a suitable supporting surface; and the object of the invention is to provide a device of this general character having novel and improved means whereby such large or main ball is maintained in operative position with convenience and facility and revolves with a minimum of friction.

The invention consists in the details of construction and in the combination and arrangement of the several parts of my improved caster whereby certain important advantages are attained and the device is rendered simpler, less expensive and otherwise more convenient and advantageous for use, all as will be hereinafter more fully set forth.

The novel features of the invention will be carefully defined in the appended claim.

In order that my invention may be better understood, I will now proceed to describe the same with reference to the accompanying drawings, wherein—

Figure 1 is a view in elevation, partly in section, of a caster constructed in accordance with an embodiment of my invention; Fig. 2 is a sectional view taken substantially on the line 2—2 of Fig. 1; and Fig. 3 is a fragmentary view in elevation of an under surface of one of the annular members.

As disclosed in the accompanying drawings, 1 denotes an attaching shank or stem adapted to be inserted in the usual manner within the furniture or the like projecting upwardly from the head or enlargement 2 of suitable configuration, and from such head or enlargement 2 project a series of curved arms 3 extending downwardly from the head or enlargement 2.

The arms 3 are adapted to conform to the periphery of the large or main ball 4 and are of such a length as to terminate below the horizontal center thereof and connected to such arms 3 above and below the horizontal center of the large or main ball 4 are the

annular members or rings 5, the connections 6 between such annular members or rings 5 and the arms 3 being of a detachable character so that the large or main ball 4 may be properly positioned, such connections 6 being herein disclosed as in the nature of inwardly directed headed members loosely disposed through the arms 3 and in threaded engagement with the annular members 5, as is thought to be clearly shown in Fig. 1 of the accompanying drawings.

In view of the foregoing, it is thought to be obvious that the arms 3 and the annular members or rings 5 afford a cage member which effectively maintains the main or large ball 4 against displacement yet permits the same to freely rotate. In order that any resultant friction may be reduced to a minimum, I find it of advantage to provide the annular members or rings 5 at points intermediate adjacent arms 3 with the elongated recesses or pockets 7, each of which being adapted to receive a plurality of anti-friction members 8 herein shown as spherical bodies, which anti-friction members 8 being constantly in contact with the periphery of the large or main ball 4. I also find it of advantage to have the arms 3 above each of the annular members or rings 5 provided with a pocket or recess 9 to accommodate additional anti-friction members 10 also herein disclosed as spherical bodies adapted to engage the periphery of the large or main ball 4.

From the foregoing description, it is thought to be obvious that a caster constructed in accordance with my invention is of an extremely simple and comparatively inexpensive nature and is particularly well adapted for use by reason of the convenience and facility with which it may be assembled and by reason of the effectiveness which it performs its several functions, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

A device of the character described comprising a head provided with an engaging shank, downwardly disposed elongated arcuate arms radiating from said head, said

arms being longitudinally curved, a main ball adapted to be received within such arms and projecting beyond the free extremities thereof, annular members disposed above and below the horizontal center of the main ball in contact with the inner faces of the arms, inwardly disposed headed members directed through the arms and the annular members for maintaining the same in operative assemblage, said annular members, intermediate the arms, being provided with elongated circumferentially disposed pockets, a plurality of anti-friction members mount-

ed within each of said pockets and adapted to contact with the main ball, the elongated arms above each of the annular members being provided with a pocket, and an anti-friction member mounted within each of said pockets.

In testimony whereof I hereunto affix my signature in the presence of two witnesses.

ORVILLE G. WALLACE.
